UNITED STATES PATENT OFFICE.

CHARLES I. Dangler and Henry Ruppel, of Cleveland, Ohio, Assignors to the Dangler Stove and Manufacturing Company, of Same Place.

DESIGN FOR AN AIR-HEATER, &c.

SPECIFICATION forming part of Design No. 23,277, dated May 15, 1894.

Application filed March 19, 1894. Serial No. 504,325. Term of patent 7 years.

To all whom it may concern:

Be it known that we, CHARLES I. Dangler and HENRY RUPPEL, citizens of the United States, and residents of Cleveland, in the county of Cuyahoga and State of Ohio, have invented and produced a new and original Design for Air Heaters and Radiators, of which the following is a full, clear, and exact description, reference being had to the drawing 10 making part of this specification.

The single figure shown in the drawing is a perspective view of our new design of heater and radiator, showing especially the front and top thereof.

15 The design is comprised in the three cylindrical tubes, A and B, B, standing side by side with an open space between them, the center one of which has a perceptibly larger diameter or cross-section than the side tubes, and 20 terminates some distance above the base and apart therefrom. A cap C, with a substantially rectangular top part and suitable surface ornamentation covers the three tubes and extends in all directions outward beyond the 25 same.

D is the base of the heater provided with attractive surface decorations, and a border piece E of scroll work or other appropriate design is set across the lower ends of the tubes immediately above the base. This border extends upward at its center over the lower end of the middle tube, but is partly broken away in the drawing to clearly show that the end of the tube is above the base. This border is a decoration in its effect. It 30 is curved inward somewhat about the tubes and runs about the same height on the middle tube as it does on the side tubes. 35

Having thus described our invention, what we claim as new, and desire to secure by Letters Patent, is—

The design for an air heater and radiator as shown and described.

CHARLES I. Dangler.
HENRY RUPPEL.
